COMBINATION NEUTRAL PRESSURE POINT
ADJUSTER AND DRAFT DIVERTER

Carl B. Lockhart, Youngstown, Ohio

Application April 20, 1950, Serial No. 156,976

4 Claims. (Cl. 126—307)

1

This invention relates generally to draft diverters and more particularly to a draft diverter incorporating a neutral pressure point adjuster.

The principal object of the invention is the provision of a simple and economic draft diverter incorporating means for restricting the inlet orifice of the draft diverter to provide a simple and convenient neutral pressure point adjustment.

A further object of the invention is the provision of a draft diverter for a gas fired heating system and particularly a heating system utilizing a conversion burner and requiring modification of the flue communication means to establish a neutral pressure point with respect to the volume of gas introduced into the heating unit and the size of the flue communication means.

A still further object of the invention is the provision of a combination draft diverter and neutral pressure point adjuster for a gas fired furnace and which device meets the American Gas Association requirements for such equipment.

A still further object of the invention is the provision of a draft diverter having a neutral pressure point adjustment member which becomes a permanent and fixed part of the draft diverter and communicating flue once the adjustment is made.

A still further object of the invention is the provision of a neutral pressure point adjuster for a furnace having a gas conversion burner installed therein and eliminating the need of blocking off the flue area of the furnace.

It is well known in the art that many and various forms of gas conversion burners are being installed in furnaces, boilers and other heating equipment initially designed for burning solid fuel. It is also known in the art that installation of such conversion burner equipment requires the modification or adjustment of the heating equipment and particularly the flue means thereof to render the heating equipment efficient in the use of gas as a fuel. It has been the custom in making such conversion burner installation to block off portions of the flue structures of the equipment so as to achieve a desirable neutral pressure point in the heating equipment and under which condition the gas fuel may be efficiently burned and the heat therefrom efficiently transferred by the furnace to the heating medium employed. It is also known that such installations require the use of a draft diverter in the means establishing communication between the heating equipment and the flue in order that no draft from the flue will effect the efficient operation of the heating equipment.

2

The present invention relates to a draft diverter of the type generally approved by the American Gas Association for installation in connection with gas conversion burners and incorporates with the draft diverter a neutral pressure point adjuster which comprises a baffle for restricting the inlet orifice of the draft diverter, that orifice which establishes communication with the heating equipment and through which orifice the products of combustion are introduced into the draft diverter. The utilization of the combination draft diverter and neutral pressure point adjuster disclosed herein eliminates the necessity of blocking off the flue areas of the heating equipment and makes possible the use of standard size flue communicating piping with various sizes of gas conversion burners by enabling the communicating means to be correctly restricted to match the particular input of the burner and thereby achieve satisfactory and economic operation.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a perspective view of the draft diverter and neutral pressure point adjuster.

Figure 2 is a top plan view taken on line 2—2 of Figure 1.

Figure 3 is a detail of a neutral pressure point adjuster portion of the device shown in Figures 1 and 2.

By referring to the drawings and Figure 1 in particular it will be seen that a combination draft diverter and neutral pressure point adjuster has been disclosed which comprises a square box-like structure including side walls 10 and 11, a rear wall 12 and a front wall 13 and a top wall 14. The bottom portion of the device is open to the atmosphere. The top wall 14 has a large central opening and an upstanding fluted collar 15 affixed thereto and is adapted to be connected with a flue by suitable means (not shown). The front wall 13 has a large central opening and an annular projecting flange 16 secured therein and forming means in which a communicating pipe from a heating device may be positioned so that the products of combustion from the device are delivered into the draft di-

verter through the opening in the front wall 13.

As is customary in draft diverter construction a diagonally positioned semi-V-shaped baffle 17 is secured to the top 14 of the draft diverter near the front wall 13 and, as best illustrated in Figure 2, wherein the baffle 17 is illustrated as being secured to the top 14 by a pair of spaced rivets 18 positioned through a flange 19 on the baffle 17.

Still referring to Figure 2 of the drawings it will be observed that the point of attachment of the baffle 17 to the top 14 is spaced with respect to the front wall 13 and that the top 14 has a transverse slot 20 formed therein immediately adjacent the front wall 13 and of a width extending practically from the one side wall 10 to the other side wall 11. L-shaped guides 21 are secured to the side walls 10 and 11 and with the adjacent front wall 13 form vertical channels for the reception of a rectangular body member 22 having a transversely positioned, forwardly extending flange 23 along its uppermost edge as best shown in Figure 3 of the drawings.

The body member 22 comprises the neutral pressure point adjuster and is adapted to be positioned in the draft diverter by engaging the same in the slot 20 and moving the same downwardly in the channels defined by the front wall 13 and the guides 21—21 heretofore referred to which will frictionally engage the same. In such position the body member 22 forms a restriction or partial closure with respect to the large opening in the front wall 13 as defined by the annular projecting flange 16 heretofore referred to. The body member 22 is shown in position in Figures 1 and 2 of the drawings and in Figure 1 dotted lines indicate the partial positioning of the body member 22 in the device as, for example, at the time the same is being installed therein.

By referring now to Figure 3 of the drawings it will be seen that the body member 22 has a calibrated scale formed vertically thereon and which scale may be applied thereto as with a rubber stamp or other suitable means. The scale indicates the portion of the body member 22 to be cut off to enable the body member 22 to correspond with the input rating of the heating device on which the combination draft diverter and neutral pressure point adjuster is installed. For example, the device when installed in a heating system with a rated input of 80,000 B. t. u. will be utilized in the full length supplied and as shown in Figure 3 of the drawings with the dotted line extension on the lower portion thereof. When the device is installed in a heating system having 100,000 B. t. u. input rating, the body member 22 will be cut transversely at the 100,000 marking on the scale provided and the shortened body member 22 then installed in the draft diverter as shown in Figures 1 and 2 of the drawings and heretofore described.

The annular flange 16 and the upstanding collar 15 are of standard six inch size so that six inch flue connecting piping may be employed with the device and the economies achieved from standardization of flue connecting piping and draft diverter will occur to those skilled in the art. It will also occur to those skilled in the art that by using the combination draft diverter and neutral pressure point adjuster disclosed herein the majority of heating system conversions can be accommodated through the use of standard parts as aforesaid while enabling a speedy and efficient adjustment of the flue restriction by the body member 22 to achieve the desired neutral pressure point for the particular system.

It will also occur to those skilled in the art that the device is economical in use in that it replaces a conventional draft diverter which is required in the installation of a gas conversion burner and that the guides 21 and the body member 22 comprise the only additional construction added to the draft diverter to form the composite article herein disclosed.

It will thus be seen that the several objects of the invention have been met by the draft diverter and neutral pressure point adjuster disclosed herein.

Having thus described my invention, what I claim is:

- 15 1. A combination draft diverter and neutral pressure point adjuster comprising a box-like device open at its bottom and having inlet and outlet openings communicating therewith, and a baffle positioned between said openings, said inlet opening formed in one of the side walls of the said box-like device, a transverse slot in the top wall of the said device adjacent the wall in which the said inlet opening is formed, guides positioned on the oppositely disposed side walls of the device adjacent the wall in which the said inlet opening is formed and a body member movably positioned through said slot and in registry with said guides and partially closing the said inlet opening.
- 20 2. A combination draft diverter and neutral pressure point adjuster comprising a box-like device open at its bottom and having inlet and outlet openings communicating therewith, and a baffle positioned between said openings, said inlet opening formed in one of the side walls of the said box-like device, a transverse slot in the top wall of the said device adjacent the wall in which the said inlet opening is formed, guides positioned on the oppositely disposed side walls of the device adjacent the wall in which the said inlet opening is formed, a body member movably positioned through said slot and in registry with said guides and partially closing the said inlet opening, and a transversely extending outturned flange on the upper edge of the said body member for limiting the downward movement of said body member in the said slot.
- 25 3. A combination draft diverter and neutral pressure point adjuster comprising a box-like device open at its bottom and having inlet and outlet openings communicating therewith and a baffle positioned between said openings, said inlet opening formed in one of the side walls of the said box-like device and the outlet opening formed in the top wall of the box-like device, a transverse slot in the top wall of the said device spaced with respect to the outlet opening and adjacent the wall in which the said inlet opening is formed, vertical guides on the oppositely disposed side walls of the device adjacent the wall in which the said inlet opening is formed and a flat body member movably positioned through said slot and in registry between said guides and said wall and partially closing the said inlet opening, said body member formed of sheet metal and adapted to be cut off to provide a desired degree of closure with respect to said inlet opening.
- 30 4. In a draft diverter having a box-like body open at the bottom, an inlet opening on one side and an outlet opening on the top and a baffle diagonally positioned in the draft diverter between the said openings, a neutral pressure point adjuster comprising a sheet-like body member

movably vertically in said box adjacent the said inlet opening for partially blocking the same, the said box having channels formed adjacent the said opening for receiving the said sheet-like body member and retaining the same in position by friction.

CARL B. LOCKHART.
